MECHANISM FOR TYPESETTING MACHINES

Joseph Urban, Detroit, Mich.

Application April 6, 1944, Serial No. 529,850

9 Claims. (Cl. 199—45)

This invention relates to mechanisms for type setting machines. In such machines it is customary to provide a plurality of magazines each containing types of a different size, and a corresponding number of molds each adapted to receive types from one of the magazines. Before the machine is used the magazine containing the types of the size required is set at its type-discharging position and the corresponding mold is set at its type-receiving position, for if the wrong mold is left in type-receiving position the result will not be satisfactory. However as these two operations are now entirely separate and distinct, and depend upon separate adjustments made by the operator, it not infrequently happens that synchronizing adjustments are not made with the result that the proper mold is not in position to receive the type discharged from the magazine in operative position.

This invention aims, among other things, to provide a mechanism for type setting machines through which movement of the magazines to bring any one of them to its type-discharging position simultaneously moves the molds so that the mold corresponding to that magazine is brought to its type-receiving station.

Another object of the invention is to provide such a mechanism which is so arranged that upon arrival of any one of the magazines at its type-discharging position the drive means through which the molds are rotated by movement of the magazines is automatically disconnected thereby permitting rotation of the molds without imparting any movement to the magazines. This is necessary because from time to time during use of a mold it has to be turned from its type-receiving to its type-casting position and back to its type-receiving position. However during these movements errors in adjustment of the molds relative to their magazines are not likely to occur.

A further object of the invention is to provide a mechanism for type setting machines for controlling the setting of the molds by movement of the magazines which may either be built into a machine or applied to a machine already in use.

Having thus briefly and broadly stated some of the objects and advantages of the invention I will now proceed to describe it in detail with the aid of the accompanying drawings, in which:

Figure 1 is a partial front elevation of a conventional type setting machine whereon my mechanism is shown, and

Figure 2 is a side elevation thereof.

Figure 3 is an enlarged view of the magazine moving mechanism.

Figure 4 is a view on the line 4—4 of Figure 3. Figure 5 is an enlarged partial view on the line 5—5 of Figure 1.

Figure 6 is a section on the line 6—6 of Figure 5. Figure 7 is a section on the line 7—7 of Figure 6.

Figure 8 is a partial plan view of the parts shown in Figure 7 and includes the shifter.

Figure 9 is a plan view of a part of my mechanism taken in the direction of the arrow 9 of Figure 2 omitting the rack which meshes with the pinion.

Figure 10 is a side view on the line 10—10 of Figure 9 showing also the chain drive to the lower sprocket wheel.

Figure 11 is a perspective view showing the magazines and their moving means.

Figures 12 and 13 are sections on the line 12—12 and 13—13 respectively of Figure 2.

Figure 14 shows a modification of my mechanism applied to a different known type of magazine movement.

Figure 15 is a plan view of part of my mechanism shown in Figure 14 in the direction of the arrow 15 thereon.

Figure 16 is a side view in the direction of the arrow 16 in Figure 15 and includes also the chain drive to the lower sprocket wheel.

I will first describe the parts of a conventional type setting machine with which my invention cooperates, as it is of course realized that such a machine performs various operations, such as selectively delivering types to the mold in position to receive them, type casting and the like, all of which has no bearing on my mechanism, so the means employed for so doing is largely ignored both in the drawings and the specification for the sake of both clarity and brevity.

Provided upon the upper part of the machine are a plurality of parallel, vertically spaced magazines, 2, 3, 4 and 5 which are downwardly inclined toward their front extremities and are relatively downwardly and rearwardly stepped at their ends. These magazines are held in parallel spaced relation as by straps 6. Integral

with opposite sides of the frame 1 of the machine are substantially horizontal arms 7 slotted at 8 intermediately of their length and extending along the lower faces of the slots are racks 9. Extending transversely of the machine beneath the bottom magazine 5 and through the slots 8 is a crank shaft 10 having pinions 11 fixed thereon which engage the racks 9, and the cranked portion of the shaft 10 passes through bearings 12 depending from the bottom magazine 5. Thus upon rotation of the crank shaft

50

10 not only is the latter moved longitudinally in the slots 8 by engagement of the pinions 11 with the racks 9 thereby moving the magazines 2, 3, 4 and 5 forwardly or rearwardly, but the said magazines are also raised or lowered by the crank shaft 10. In this manner the lower discharge end of any one of the magazines may be brought into registry with the upper end of a chute 14. Fixed on the crank shaft 10 is a sprocket wheel 15 having a chain 16 passing around it which also passes around an intermediate sprocket 17, and mounted coaxially with the latter for rotation therewith is another sprocket wheel 18 around which another chain 19 passes which also extends around a sprocket wheel 20 fixed on a spindle 21 which is turned through a crank handle 22. Links 23 through which the ends of the crank shaft 10 extend are provided at their opposite extremities with rollers 24 which ride along substantially horizontal guides 25 formed upon the rear upper portions of the arms 7 as the crank shaft is rotated.

Mounted beneath the magazines 2, 3, 4 and 5 at right angles to the axis of the crank shaft 10 is a horizontal shaft 25 having a ring gear 26 thereon which supports four molds 27, 28, 29 and 30 arranged substantially to form four sides of a square though with their extremities spaced from one another. From the chute 14 types are delivered by a conventional delivery means indicated at 14a to whichever mold is at that time located at the position a. If therefore the molds 27, 28, 29 and 30 are designed to receive types from the magazines 2, 3, 4 and 5 respectively when the magazine 5 is in position to discharge types into the chute 14 the mold 30 is at the position a to receive it. Mounted on the machine is a drive shaft 31 having an axially movable gear 32 freely mounted thereon which always remains in mesh with ring gear 26. Fixed on the shaft 31 is a disc 33 having a forwardly projecting drive pin 34 to engage an aperture 35 formed in the rear face of the gear 32 and drive the latter. Formed integral with the gear 32 is an annular axial projection 36 which extends forwardly around the shaft 31 and terminates at its front extremity in a flange 37 of increased diameter. The projection 36 is also provided with spring means 36a tending to retain the gear 32 at its rearward position shown and engaged by the driving pin 35.

The purpose of the invention is to provide an attachment for corelating the rotation of the ring gear 26 with the movement of the magazines 2, 3, 4 and 5 so that if one of the latter is positioned to discharge types into the chute 14 and the proper mold 27, 28, 29 or 30 is in the position a to receive the types, any subsequent adjustment made to move another magazine to type-discharging position will also move the corresponding mold to its type-receiving station; however the attachment is so constructed and arranged that the ring gear 26 and its molds 27, 28, 29 and 30 may be freely rotated when any magazine is at its type-discharging position because, as previously stated, during the use of a mold it is necessary from time to time to turn the gear and move that mold from its type-receiving position a to its type-casting position b and then back to its original type-receiving station.

Extending from one side of the frame 1 are bearings 39 which support a shaft 40 for rotation; fixed on one extremity of the latter is a

gear 41 and mounted for both free rotation and axial movement on the other extremity of the shaft 40 is a gear 42 having a grooved collar 43 integral with its rear face and an aperture 44 formed in its front face. Fixed also upon the shaft 40 in front of the gear 42 is a collar 45 having a driving pin 46 projecting toward the gear 42 and adapted to engage the aperture 44. Between the gear 42 and the collar 45 a spring 47 is provided which tends to retain the collar 43 integral with the gear 42 in contact with one of the bearings 39 and the said gear spaced from the collar 45 so that the driving pin 46 is disengaged from the aperture 44.

Mounted also upon the frame 1 are other bearings 48 which support a shaft 49 having a sprocket wheel 50 and a gear 51 fixed thereon. The gear 51 meshes with the gear 41 and formed on its front face is an annular cam 52 which is flat around the major portion of its circumference and is provided with one relatively sudden, narrow depression 53. Mounted for axial movement in bearings 54 is a rod 55 one extremity of which bears against the cam 52 and provided on the opposite extremity of the rod are two shifter yokes 56 and 57. The yoke 56 engages the grooved collar 43 and the yoke 57 bears against the rear face of the flange 38, so that forward movement of the rod 55, through the yokes, moves the gear 42 into engagement with the driving pin 46 whereupon the said gear turns with the shaft 40, and also disengages the gear 32 from the driving pin 35 so that the said gear 32 may turn freely upon the shaft 31.

35 A pin 60 which forms the axle for one of the rollers 24 also extends through a member 58 having a rack 59 on its underside, thereby pivotally connecting the said member to one of the links 23. Formed longitudinally through the member 58 40 intermediately of its length is a slot 61 having a roller 62 mounted for rotation therein, and extending from an upright 63 mounted on the frame 1 is a brace 64 on the outer extremity of which the roller 62 is rotatably secured. Thus the brace 64 and roller 62 serve to support the extremity of the member 58 remote from the roller 24 and permit movement of the said member as the roller 24 travels along its guide 25.

50 Mounted also on the frame 1 is a bracket 65 integral with which are two bearings 66 and 67 arranged at right angles to one another. The bearing 66 supports a shaft 68 having a sprocket wheel 69 and a bevel gear 70 fixed thereon, and the bearing 67 supports a shaft 71 having a bevel gear 72 thereon which meshes with the bevel gear 70 and a pinion 73 which engages the rack 59. A chain 74 extends around the sprocket wheels 69 and 50 to impart a drive from the shaft 68 to the shaft 49.

60 From the foregoing it will be clearly seen that movement of the magazines 2, 3, 4 and 5 through their conventional operating mechanism including the crank handle 22 causes movement of the rollers 24 along their guides 25. When this occurs the member 58 is also moved so that its rack 59 turns the pinion 73. Rotation of this pinion through the gearing just described turns the sprocket wheel 69 thereby driving the shaft 49 and gear 51 through the chain 74 and sprocket wheel 50. This drive is so proportioned that each time one of the magazines reaches its type-discharging position the gear 51 is so positioned that the depression 53 in the cam 52 is engaged by the rod 55 which is held in contact with the cam by the flange 37 which is rearwardly urged

by the spring means 36a. When the rod 55 is in its rearward position the gear 42 is pulled back out of engagement with the driving pin 46 by the yoke 56 and the yoke 57, when in its rearward position, allows the gear 32 to move rearwardly into engagement with its driving pin 35. The drive means is also so proportioned that each time one of the magazines reaches its type-discharging position the mold which cooperates with that magazine is at its type-receiving station. When it is desired to turn the gear 32 by hand on its shaft 31 to turn one of the molds from its type-receiving to its type-casting position, or vice versa, it is merely necessary to pull the projection 36 forward and thereby disengage the gear 32 from its driving pin 35. Then rotation of the gear 32 also turns the gear 42 which at that time is free on its shaft 40.

As soon as the magazines 2, 3, 4 and 5 commence to move the gear 51 commences to turn and the rod 55 is disengaged from the depression 53 by rotation of the cam 52 and is moved forwardly. The yoke 56 moves the gear 42 into engagement with the driving pin 46 and the yoke 57 moves the gear 42 out of engagement with the driving pin 35. Consequently rotation imparted through the gear 51 turns the shaft 40, the gear 42, and the ring gear 25 through the gear 32 which is then free to rotate on the drive shaft 31.

In Figures 14, 15 and 16 a modified and well known arrangement for adjusting the positions of the magazines 2a, 3a, 4a and 5a to set any one of them in registry with the upper extremity of the chute 14b is shown and in cooperation with it is a somewhat modified arrangement of the upper portion of my mechanism for imparting correlated movement to the molds.

In this instance an inclined post 80 is provided which at its upper extremity is secured to the lowest magazine 5a, it being understood of course that the magazines are again held in spaced parallel relation to one another, though in this instance an imaginary line extending across the ends of all the magazines at either extremity is parallel with the axis of the post 80. Provided on the latter is a rack 81 meshing with which is a pinion 82 fixed on a shaft 83 that also has a worm wheel 84 thereon. In engagement with the latter is a worm 85 on a spindle 86 which is connected to other spindles 87 and 88 through universal connections 89 and 90 respectively. Upon the spindle 88 is a crank 91 by rotation of which the spindles 88, 87 and 86 are turned thereby turning the worm 85, the worm wheel 84, and the pinion 82 thus moving the rack 81 and post 80 longitudinally so that any one of the magazines may be brought into registry with the chute 14b.

In this instance a rack 59a is secured to one side of the magazines parallel with the path of movement of the post 80. This rack 59a is engaged by a pinion 73a mounted on a shaft 71a supported by a bearing 67a carried on a bracket 65a which also has a second bearing 66a thereon. Fixed also on the shaft 71a is a bevel gear 72a which meshes with a second bevel gear 70a on a shaft 68a supported in the bearing 66a. Secured also around the shaft 68a is a sprocket wheel 69a which drives the sprocket wheel 50 on the shaft 49 through a chain 74a.

It will be noted in the drawings that the chain 74, or 74a, is shown passing around guide sprockets 94 mounted on suitable supports 95. Obviously any desired arrangement of guide sprockets may be utilized to carry the chain in such a man-

ner that it will not interfere with the operation of other parts of the machine.

While in the foregoing the preferred embodiments of the invention have been described and shown it is understood that alterations and modifications may be made thereto provided the said alterations and modifications fall within the scope of the appended claims.

What I claim is:

10. In a type setting machine comprising a plurality of magazines mounted for movement, a chute including delivery means adjacent its lower extremity, means for moving any one magazine into registry with the upper end of the chute, a ring gear mounted for rotation, and a plurality of molds supported by the ring gear any one of which may be moved into registry with said delivery means by rotation of the ring gear, the combination of gearing cooperating with the ring gear, and means actuated by movement of the magazines for rotating the gearing.
20. In a type setting machine comprising a plurality of magazines mounted for movement, a chute including delivery means adjacent its lower extremity, means for moving any one magazine into registry with the upper end of the chute, a gear mounted for rotation, and a plurality of molds supported by the gear any one of which may be moved into registry with said delivery means by rotation of the gear, the combination of gearing cooperating with said gear, means actuated by movement of the magazine for rotating the gearing, and said gearing including release means whereby when rotation is imparted to said gear the magazines remain stationary.
30. In a type setting machine comprising a plurality of magazines mounted for movement, a chute including delivery means adjacent its lower extremity, means for moving any one magazine into registry with the upper end of the chute, a gear mounted for rotation, and a plurality of molds supported by said gear any one of which may be moved into registry with said delivery means by rotation of the gear, the combination of gearing cooperating with said gear, means actuated by movement of the magazine for rotating the gearing, and said gearing including release means whereby when rotation is imparted to said gear the magazines remain stationary.
40. In a type setting machine comprising a plurality of magazines mounted for movement, a chute including delivery means adjacent its lower extremity, means for moving any one magazine into registry with the upper end of the chute, a gear mounted for rotation, and a plurality of molds supported by said gear any one of which may be moved into registry with said delivery means by rotation of said gear, the combination of a rack mounted for movement with the magazines, a pinion mounted for rotation by said rack upon movement of the magazines, gearing cooperating with said gear, and means for turning said gearing by rotation of said pinion.
50. In a type setting machine comprising a plurality of magazines mounted for movement, a chute including delivery means adjacent its lower extremity, means for moving any one magazine into registry with the upper end of the chute, a gear mounted for rotation, and a plurality of molds supported by said gear any one of which may be moved into registry with said delivery means by rotation of said gear, the combination of a rack mounted for movement with the magazines, a pinion mounted for rotation by said rack upon movement of the magazines, gearing cooperating with said gear, means for turning said gearing by rotation of said pinion, and said gearing including release means whereby when rotation is imparted to said gear the magazine remains stationary.
60. In a type setting machine comprising a plurality of magazines mounted for unitary movement, a chute having a delivery means extending from its lower extremity, means for moving the magazines to bring any one of the latter into registry with the upper end of the chute, a gear mounted for rotation, a plurality of molds supported thereby any one of which may be brought into registry with said delivery means by rota-
70. In a type setting machine comprising a plurality of magazines mounted for unitary movement, a chute having a delivery means extending from its lower extremity, means for moving the magazines to bring any one of the latter into registry with the upper end of the chute, a gear mounted for rotation, a plurality of molds supported thereby any one of which may be brought into registry with said delivery means by rota-

tion of said gear, a drive shaft, a gear freely mounted thereon meshing with the first named gear, and means on the drive shaft for engaging the gear for rotation with said drive shaft, the combination of gearing including another shaft having a gear freely mounted thereon meshing with the gear on the drive shaft, means on said other shaft for engaging the gear thereon for rotation therewith, means for imparting rotation to said gearing by movement of said magazines, and means whereby when the gear supporting the molds is turned by rotation of the drive shaft and through the gear thereon the means for transmitting the magazine movement to said gearing remains stationary.

6. In a type setting machine, the combination of a plurality of magazines, a chute including delivery means extending from its lower extremity, means for moving the magazines and bringing any one of them into registry with the upper portion of the chute, a gear mounted for rotation, a plurality of molds supported by the gear any one of which may be brought into registry with the delivery means by rotation of said gear, gearing cooperating with said gear, and means actuated by movement of the magazines for imparting rotation to said gearing.

7. In a type setting machine, the combination of a plurality of magazines, a chute including delivery means extending from its lower extremity, means for moving the magazines to bring any one of them into registry with the top of the chute, a gear mounted for rotation, a plurality of molds supported by the gear any one of which may be brought into registry with the delivery means by rotation of said gear, a drive shaft having a gear freely mounted thereon meshing with the aforesaid gear, gearing including another shaft having a gear freely mounted thereon and meshing with the gear on the drive shaft, separate means for engaging the freely mounted gears whereby each is engaged for rotation with its shaft, shifter means for moving both the engaging means so constructed and arranged that one of the freely mounted gears is engaged when the other is disengaged, and means carried by the gearing for actuating the shifter means.

8. In a type setting machine, the combination of magazines mounted for unitary movement, a chute including delivery means extending from its lower extremity, means for moving the magazines to bring any one into registry with the upper portion of the chute, a rack mounted for

movement with the magazines, a pinion meshing with the rack and rotated by movement thereof, an upper drive means actuated by rotation of the pinion, a gear mounted for rotation, a plurality of molds supported thereon any one of which may be brought into registry with the delivery means by rotating the gear, a drive shaft having a gear freely mounted thereon meshing with the first gear, means on the drive shaft for engaging the gear thereon whereby said gear is turned by rotating the drive shaft, another shaft having a gear freely mounted thereon and meshing with the gear on the drive shaft, means on said other shaft for engaging the gear thereon whereby said gear is turned by rotation of the other shaft, a third shaft mounted for rotation, means for driving the third shaft by said upper driving means, means for driving said other shaft from said third shaft, a shifter cooperating with the two engaging means for the freely mounted gears so constructed and arranged that one gear is engaged on its shaft and the other is disengaged upon movement of said shifter, and means actuated by rotation of said third shaft for moving the shifter.

9. In a type setting machine, the combination of magazines mounted for unitary movement, a chute including delivery means extending from its lower extremity, means for moving the magazines and bringing any one into registry with the top of the chute, a rack mounted for movement with the magazines, a pinion rotated by movement of the rack, a sprocket wheel turned by rotation of the pinion, a gear mounted for rotation, a plurality of molds supported thereby any one of which may be brought into registry with the delivery means by rotation of the gear, a drive shaft having a gear freely mounted thereon meshing with the first named gear, another shaft having a gear freely mounted thereon meshing with the gear on the drive shaft, separate means on the drive shaft and on the other shaft for engaging the gears thereon respectively whereby each turns with its shaft, a third shaft having a gear and a sprocket wheel fixed thereon, a gear fixed on said other shaft meshing with the last named gear, a drive chain around both sprocket wheels, a cam on said third shaft, a shifter operated by the cam, said shifter coacting with the two means for engaging the freely mounted gears whereby one gear is engaged for rotation with its shaft when the other gear is disengaged.

JOSEPH URBAN.
